UNITED STATES PATENT OFFICE.

HOWARD A. STONE, OF PHILADELPHIA, PENNSYLVANIA, ASSIGNOR TO
A. M. COLLINS MANUFACTURING COMPANY, OF PHILADELPHIA,
PENNSYLVANIA, A CORPORATION OF PENNSYLVANIA.

DESIGN FOR A CARD-MOUNT.

No. 37,945.

Specification for Design.

Patented April 10, 1906.

Application filed February 23, 1906. Serial No. 302,643. Term of patent 3½ years.

To all whom it may concern:

Be it known that I, HOWARD A. STONE, a citizen of the United States, and a resident of Philadelphia, Pennsylvania, have invented a certain new, original, and ornamental Design for a Card-Mount, of which the following is a specification, reference being had to the accompanying drawing, forming part thereof.

I claim—

The ornamental design for a card-mount, as shown.

HOWARD A. STONE.
